UNITED STATES PATENT OFFICE.

LEROY S. PFOUTS, OF CANTON, OHIO, ASSIGNOR, BY MESNE ASSIGNMENTS, TO THE
H. H. MILLER INDUSTRIES COMPANY, OF CANTON, OHIO, A CORPORATION OF
OHIO.

PASTEURIZING APPARATUS.

Application filed June 16, 1916. Serial No. 104,129.

To all whom it may concern:

Be it known that I, LEROY S. PFOUTS, a citizen of the United States, residing at Canton, in the county of Stark and State of Ohio, have invented certain new and useful Improvements in and Relating to Pasteurizing Apparatus, of which the following is a specification.

This invention relates to pasteurizing apparatus, and particularly to apparatus adapted to treat liquid, such as milk.

One object of the invention is to provide an improved apparatus for treating liquid, such as milk.

Another object of the invention is to provide a liquid treating apparatus of simplified construction, the parts of which may be readily dismembered for cleaning.

Another object of the invention is to provide improved liquid treating apparatus adapted to convey the liquid to and from the holding tanks in a manner which prevents frothing, undue agitation or splashing of the liquid.

Another object of the invention is to provide improved apparatus by which every part of the liquid is discharged into and then from the holders to insure uniform treatment thereof.

With these and other objects in view, the invention consists of the part or parts and combinations of parts or their equivalents hereinafter described and set forth in the appended claims.

My invention is adapted for use in connection with liquid treating apparatus such as shown and described in my Patent No. 1,183,764 dated May 16, 1916. It will be understood, however, that my improvements in liquid holding and distributing mechanism for pasteurizing apparatus may be used in connection with a liquid treating apparatus of any suitable or preferred construction, and while the embodiment of the

invention illustrated herein has been conformed to co-operate with the general construction of apparatus shown in my aforesaid patent, it may be adapted to suit any particular construction of apparatus in connection with which it may be used.

For the purpose of illustration I have, in the accompanying drawings, shown and herein described one form of apparatus embodying my invention.

Fig. 1 is a view, partly in side elevation 55 and partly in section, of a holding and distributing mechanism embodying my invention.

Fig. 2 is a fragmentary view, on the line 2—2 of Fig. 1. 60

Fig. 3 is a fragmentary sectional view on the line 3—3 of Fig. 1.

In the drawings, 2 indicates a base of any suitable construction, but preferably formed from metal. The base 2 may comprise an 65 annular member 2^a and a plate 2^a'. The member 2^a is preferably provided with flanges 2^b, 2^c, around its opposite peripheral edges, the flange 2^b serving as a bearing surface which rests on the floor and the 70 flange 2^c serving as a support for the plate 2^a', the latter being secured to the flange 2^c in any well known manner. At 2^a the plate 2^a' is formed with an opening to receive a liquid receiving vessel 3, which will 75 be later described.

2^e indicates one or more cross members, preferably integrally connected at their opposite ends to the wall of the annular member 2^a. The cross bars 2^e carry a vertically 80 arranged axial member 2^f having a bearing to receive a shaft or rod 4' of a valve mechanism 4 which will be later described. At its lower end the rod 4' has fixed to it a worm gear 4^x. 85

2^g indicates a plurality of lugs depending from one of the cross bars 2^e. These lugs are bored to receive and support the inner end of a driven shaft 5. The opposite end of the shaft 5 is supported in a bearing 2^h 90 provided on the annular member 2^a. 5^a indicates a worm fixed to the shaft 5 and meshing with the gear 4^x to drive it in a well known manner. 5^b, 5^c, indicate fast and loose pulleys carried by the outer end 95 of the shaft 5 and adapted to receive a belt (not shown), whereby the shaft 5 may be caused to rotate.

It will be understood from the drawings that the worm gear 4^x and worm 5^a serve as 100 reduction gearing, whereby the speed of the rod 4' as compared with that of the driven shaft 5 is relatively slow.

The vessel 3 is formed with an axial opening 3^a having an upwardly extending, inwardly inclined flange 3^b which engages with the bearing member 2^f. The wall of the bearing member 2^f is preferably inclined 105

upwardly and inwardly so as to fit within the flange 3^b and serve as a support for the vessel 3. As will be understood from the drawings, the flange 3^b co-operates with the 5 outer wall of the vessel 3 to form an annular liquid receiving receptacle surrounding the rod 4'.

6 indicates a conduit connected in any desired manner with an opening formed in 10 the bottom of the receptacle 3. The conduit 6 is adapted to conduct the liquid from the receptacle to a cooler or other apparatus, or a receiving vessel associated therewith such, for example, as illustrated at B in my 15 Patent No. 1,076,604 dated October 21, 1913.

7 indicates a series of brackets mounted on the plate 2^a. The brackets are preferably inclined upwardly and extend radially of the axis of the rod 4'. The brackets support at their outer or free ends an annular table or support 8. As will be understood from the drawings, each bracket 7 is provided at its opposite ends with suitable flanges 7^a which permit the bracket to be 25 rigidly secured in a well known manner to the plate 2^a and table 8. As the flanges 7^a at the opposite ends of each bracket are inclined relative thereto, but arranged parallel to each other, it will be seen that they serve 30 to support the adjacent bracket in an inclined position and the table 8 in a horizontal position. This arrangement provides for the use of an annular table 8 of relatively large size. The brackets 7 may be T-shaped in cross-section for the purpose of 35 imparting rigidity to them.

The table or annular support 8 preferably comprises a series of arc sections 8' arranged end to end and each flanged along 40 its opposite edges to strengthen it. 8^a indicates a plurality of openings formed in the table 8 and adapted to receive a series of independent or separate holding vessels 9. The openings 8^a are preferably uniformly spaced from each other and disposed midway between the brackets 7. Each vessel 9 may comprise inner and outer walls to form a space between them. This space may be 45 filled with cork, as shown at 9^a, or some other non-conductor of heat to provide a suitable insulating jacket. Each of said vessels is preferably provided with a detachable cover 9^b. 9^c indicates a flanged ring secured to the outer wall of each vessel 9. When a 50 vessel 9 is inserted in an opening 8^a, the flange of the ring 9^c will engage with the upper surface of the table 8 and serve to maintain the vessel 9 thereon. This construction 55 serves to support the vessels in upright position and to permit their removal at will for cleaning and other purposes.

The valve mechanism 4 comprises inlet valve devices 4^a and outlet valve devices 4^b. Of the inlet valve devices 4^a, 4^c indicates a 60 member constituting a liquid receiver and

valve. The member 4^c is preferably provided with a bottom 4^d and an annular wall 4^e, which rotatably fits within a valve seat element 10. The outer wall of the valve member 4^c is preferably conically shaped and the inner wall of the valve seat element is shaped to snugly fit the outer conical wall of the valve member 4^c for well known reasons. 4^f indicates a liquid port or duct formed in the annular wall 4^e. The bottom 70 4^d of the member 4^c is preferably provided with an integral socket 4^d' to receive the upper end of the shaft or rod 4'. The socket 4^d' may be adjustably secured to the rod 4^a in any suitable manner. The valve seat element 10 preferably comprises a ring member formed with a series of openings 10^a (preferably uniformly spaced therearound and corresponding in number to the number 80 of holders or vessels 9) with which the port 4^f successively registers as said valve member rotates. 10^b indicates a series of pipe sections, preferably formed integral with the ring member 10 and extending radially therefrom, there being a pipe section for 90 each opening 10^a. The functions of the pipe sections will be later described.

The valve member 4^c is preferably provided with an enlarged detachable casing 4^c' into the upper open end of which leads the discharge end of a liquid conduit a¹⁰. The conduit a¹⁰ leads from a suitable heater as shown at A in my aforesaid Patent No. 1,076,604 dated October 21, 1913, or from any other suitable source of supply. 100

10^c indicates a pipe, leading from the outer end of each pipe section 10^b to the adjacent vessel 9. The pipe 10^c may extend through the side wall of the adjacent holder 9, near its upper end; the pipe 10^c then preferably extends in a vertical direction downwardly, as shown at 10^d, its open or discharge end terminating at a point near to or adjacent the bottom of the holder to discharge the liquid in the bottom portion 105 of the holder without unduly agitating or splashing the liquid or creating any froth. The pipe 10^c may be made of two or more sections. When the pipe 10^c is formed of two sections, as shown in the drawings, they are preferably connected by a union 10^e at a point inside of the adjacent holder. The inner end of each pipe 10^c is preferably detachably connected to the outer end of the adjacent pipe section 10^b by a coupling 10^f. 110

Of the outlet valve mechanism 4^b, 11 indicates a valve member preferably comprising a circular plate 11^a provided with a depending rim or wall 11^b, which may be of conical shape and rotatably fitted within a valve seat member 12. The valve member 11 is formed with an opening through which the rod 4' extends. The valve member is preferably adjustably secured to the rod 4' in any suitable manner. At one side and be- 115 120 125 130

between the plate 11^a and rim 11^b, the walls of the valve member 11 are thickened and formed with a duct 11^c, which conducts liquid through the valve member 11 when a vessel 9 is emptying. The receiving port of the duct 11^c leads through the rim 11^b and its opposite or discharge port opens downwardly at one side of the rod 4' to discharge the liquid into the receptacle 3. The valve seat element 12 preferably comprises a ring member formed with a series of openings 12^a (preferably uniformly spaced therearound and corresponding in number to the number of the holders 9) with which the port 11^c successively registers as said valve member rotates. 12^b indicates a series of pipe sections preferably formed integral with the ring member 12 and extending radially therefrom, there being a pipe section for each opening 12^a. The functions of these pipe sections will be later described.

13 indicates a pipe leading from the outer end of each pipe section 12^b to the adjacent vessel 9. As shown in the drawings, the outer end of the pipe 13 leads to and is connected with a pipe section 9^c by a T-member 13^a and coupling 13^b. Each vessel 9 is formed with a discharge port 9^c in its bottom and the pipe section 9^c is connected to the bottom so as to convey the liquid from the port to the adjacent pipe 13. The opposite or inner end of each pipe 13 is preferably connected to the outer end of the adjacent pipe section 12^b by a coupling 13^c.

From the foregoing description it will be understood that the pipes 10^a with their unions with the pipe section 10^b and vessels 9 and the pipes 13 with their unions with the pipe sections 12^b and vessels 9 serve as liquid tight connections between the inlet valve devices 4^a and outlet valve devices 4^b, respectively; also, that the ring member 10 and walls of the valve member 4^c constitute the inlet valve devices which control the flow of the liquid through the pipes 10^a to the vessels 9 as the port 4^c successively registers with the openings 10^a; and that the ring member 12 and walls of the member 11 constitute the outlet valve devices which control the flow of the liquid through the pipes 13 from the vessels 9 as the inlet port of the duct 11^c successively registers with the openings 12^a; as a result of this construction, it will be seen that the vessels 9 are filled progressively and discharged progressively.

During the time that the port 4^c is in registry with the opening 10^a for an adjacent vessel 9, as the valve member 4^c rotates, liquid will flow therethrough from the latter to the vessel to fill the same, the speed of the valve member and the size of the openings 4^c, 10^a, being proportioned so that during such registry thereof sufficient liquid

will flow through the valve devices to substantially fill the vessel. The liquid is held in the vessel 9 during the rotary movement of the valve mechanism 4 from the time the opening or port 4^c registers with an opening 10^a for the adjacent vessel until the inlet port of the discharge duct 11^c registers with the valve opening 12^a of the vessel 9, whereupon the liquid will flow by gravity from the vessel through the outlet valve devices to the receptacle 3. The discharge port of the duct 11^c is preferably provided with a discharge pipe 14, which directs the liquid into the receiving vessel 3. As the ducts 4^c, 11^c, and valve ports 10^a, 12^a, are of substantially the same size and the valve members 4^c, 11^c, rotate together and preferably uniformly, it will be understood that substantially the same quantity of liquid may flow out of each vessel 9 as flowed into it in the same time interval.

The valve member 11 for the outlet valve devices 4^b is preferably so arranged angularly on the rod 4' relative to the port 4^c, that the inlet port of the duct 11^c will register with the valve port 12^a for that vessel 9 next in advance of the vessel 9 which at any time is being filled with liquid through the inlet valve devices 4^a. As a result of this arrangement, each vessel will be filled immediately after it has been emptied. However, the valve members 4^c and 11 may be positioned to so arrange the ports 4^c, 11^c at any point angularly of the axis of the rod 4' relative to each other that the period during which the liquid is held may be fixed according to any particular circumstances. It will therefore be seen that the liquid may be held in the vessels 9 for any desired predetermined period, the extent of which will depend upon the length and time of travel from the place of filling to the place of discharge. It will be obvious that the speed of the valve members can be changed in various ways to increase or decrease the period between the filling and emptying of the vessels.

15 indicates a conduit leading from the pipe a¹⁰. The pipe 15 may lead directly to a suitable cooler, so as to conduct the liquid thereto when it is unnecessary to treat the liquid in the distributing and holding apparatus. I preferably provide a three-way valve at the point of connection of the pipe 15 with the pipe a¹⁰ to control the flow of the liquid to either the receiver 4^c or direct to the cooler, or to cut off the flow of the liquid entirely.

It will be understood that in the system of pasteurizing liquid to which my invention is particularly applicable and in which the liquid is maintained at a pasteurizing temperature for a predetermined period, it is desirable to quickly and uniformly heat the liquid to the predetermined temperature,

maintain the liquid at that temperature for a certain definite length of time in order to destroy or render innocuous any germs or bacteria contained in the liquid and finally 5 to cool the liquid to a normal temperature; and that it is also desirable that these steps should be carried on in a continuous and uniform manner; that is, there should be a continuous flow of the liquid to and through 10 the apparatus. The liquid is delivered to a receiving tank from which it flows to a heater. In passing through the heater the liquid is continuously and uniformly raised to the desired temperature and is discharged from 15 the heater by means of the pipe a^{10} , which conveys the liquid to the receiving member 4^c. As the valve member 4^c rotates, the port 4^f thereof successively registers with the valve openings 10^a in the ring member 10 and 20 permits a predetermined quantity of liquid to flow by gravity to each of the vessels, each duct registering with a valve port 10^a for a given period of time, in the rotary movement of the valve member sufficient, at least, to substantially 25 fill the adjacent vessel. Likewise, the discharge duct 11^c successively registers with the valve openings 12^a of the valve ring 12 and permits the automatic discharge of the vessels successively. From the foregoing 30 description and operation it will be seen that the vessels will be automatically filled and emptied at predetermined points.

The vessels 9 are preferably arranged in a circular series about the valve mechanism 4 35 in order that they may be equally distant therefrom; the valve members 4^c and 11 are preferably connected to and operated by a single driven member to simplify the construction and reduce the number of working 40 parts of the apparatus.

The inlet valve devices 4^a are separate from the outlet valve device 4^b. The devices 4^a are preferably arranged above the devices 4^b and approximately in the plane of 45 the upper edges of the holders 9. This form of construction permits me to extend each conduit 10^c for the liquid into the adjacent holder at a point above the level attained by the liquid when the vessel is filled and 50 then downwardly to a point near its bottom, rather than through the bottom of the vessel. By providing separate inlet and outlet pipes 10^c, 13, respectively, and connecting them to the upper and lower ends, respectively of the holders 9, I insure the discharge into each holder 9 of all the liquid delivered thereto before any liquid is again delivered to it.

It will be noted that all walls of the conduits and receptacles in the holding mechanism, with which any liquid to be treated may come into contact, and parts of the valve mechanism, are readily accessible for the purpose of cleaning merely by disassembling them and adjacent parts or conduits;

also, that the vessel 3, may, if desired, be removed for cleaning by disassembling the parts of the apparatus immediately above it. In fact, when said parts are removed, the tank 3 may be lifted bodily upwardly and 70 removed from the apparatus for cleaning or replacing.

By extending the liquid inlet pipes 10^c downwardly to and delivering the liquid near the bottom of each holder and then emptying the liquid through a port in the bottom thereof, I am enabled to both fill and empty the vessels without splashing the liquid, unduly agitating it or causing frothing thereof. 80

To those skilled in the art of making apparatus of the class described, many alterations in construction and widely differing embodiments and applications of my invention will suggest themselves, without departing from the spirit and scope thereof. My disclosures and the description herein are purely illustrative and are not intended to be in any sense limiting. 85

What I claim is:

1. The combination of a series of holders, inlet valve devices common to said holders, liquid tight connections between said inlet valve devices and each of said holders, outlet valve devices, separate connections between each of said holders and said outlet valve devices, and means for operating the valves of said inlet and outlet valve devices for progressively filling said holders and progressively discharging said holders. 95

2. The combination of a series of holders, inlet valve devices, liquid tight connections between said inlet valve devices and each of said holders, outlet valve devices common to said holders, separate connections between the bottom of each of said holders and said outlet valve devices, and means for rotating the valves of said inlet and outlet valve devices for progressively filling said holders and progressively discharging said holders. 105

3. In apparatus of the character described, the combination of a series of holders, a liquid supply connection for each holder connected thereto at its outer end, a liquid discharge connection for each holder connected thereto at its outer end, a valve mechanism common to the inner ends of said liquid supply connections, a separate valve mechanism common to the inner ends of said liquid discharge connections, and means for operating the valves of said valve mechanisms. 115

4. In apparatus of the character described, the combination of a series of holders, a liquid supply connection for each holder, a liquid discharge connection for each holder, a valve having a port to control the flow of liquid successively to said liquid supply connections, a separate valve having a port to control the flow of liquid 120

115

120

125

130

successively from each liquid discharge connection, and means for operating said valves.

5. In apparatus of the character described, the combination of a series of holders, a liquid supply connection for each holder leading to the upper end thereof, a liquid discharge connection for each holder leading from the lower end thereof, a valve having a port to control the flow of liquid successively to said liquid supply connections, a separate valve having a port to control the flow of liquid successively from each liquid discharge connection, and means for operating said valves.

10. 6. The combination of a series of holders, separate inlet and discharge connections for each holder leading to points adjacent the bottom thereof, a valve for controlling the flow of liquid successively to said inlet connections, a valve for controlling the flow of liquid successively from said discharge connections, and means for operating said valves.

7. The combination of a series of liquid holders, a liquid supply connection for each of said holders connected thereto at its outer end, a receiver having a discharge port arranged successively to register with the inner ends of said liquid supply connections, means for controlling the discharge of liquid from said holders, and means for operating said receiver.

8. The combination of a series of liquid holders, a liquid supply connection for each of said holders connected thereto at its outer end, a receiver having a discharge port arranged successively to register with the inner ends of said liquid supply connections, a liquid discharge connection for each holder connected thereto at its outer end, a valve common to the inner ends of said liquid discharge connections and arranged to control the discharge therefrom successively, and means for operating said receiver and said valve.

9. In apparatus of the character described, the combination of a series of holders, a liquid supply connection for each holder leading to or adjacent the bottom thereof, a liquid discharge connection for each holder leading from the bottom thereof, a valve for controlling the supply of liquid successively to said liquid supply connection, a valve for controlling the discharge of liquid successively from said liquid discharge connections, and means for operating said valves.

10. In apparatus of the character described, the combination of a series of holders, a liquid supply connection for each holder, the inner ends of said supply connections leading to a point above the level to which said holders are filled and their outer ends leading to or adjacent the bottoms thereof, a liquid discharge connection for each holder, the outer ends of said dis-

charge connections being connected to the bottoms of said holders and their inner ends extending to a point in the plane of or below said bottoms, a valve for supplying liquid successively to the inner ends of said supply connections, a valve for discharging liquid successively from the inner ends of said discharge connections, and means for operating said valves.

11. In apparatus of the character described, the combination of a series of holders each formed with an opening in its bottom, a liquid supply connection for each holder, the inner ends of said supply connections leading to a point above the level to which said holders are filled with liquid and their outer ends leading to or adjacent the bottoms thereof, a valve for supplying liquid successively to the inner ends of said liquid supply connections, and means for controlling the discharge of liquid successively through the openings in the bottoms of said holders.

12. The combination of a series of liquid holders, inlet valve devices comprising an inner member and an outer member, one of which is rotatable relative to the other, the outer member being formed with a series of valve openings and the inner member being formed with a port or duct to control the flow of liquid through the openings in the outer member, outlet valve devices comprising an inner member and an outer member, one of which is rotatable relative to the other, the outer member being formed with a series of valve openings and the inner member being formed with a port or duct to control the flow of liquid through the openings in the outer member, liquid supply connections between the outer member of the inlet valve devices and each of said holders, liquid discharge connections between each of said holders and the outer member of said outlet valve devices, and means for rotating the rotatable members of said inlet and outlet valve devices.

13. The combination of a series of liquid holders, inlet valve devices comprising an inner member and an outer member, one of which is rotatable relative to the other, the outer member being formed with a series of valve openings and the inner member being formed with a port or duct to control the flow of liquid through the openings in the outer member, outlet valve devices comprising an inner member and an outer member, one of which is rotatable relative to the other, the outer member being formed with a series of valve openings and the inner member being formed with a port or duct to control the flow of liquid through the openings in the outer member, liquid supply connections between the outer member of the inlet valve devices and each of said holders, liquid discharge connections be-

tween each of said holders and the outer member of said outlet valve devices, and means for rotating the rotatable members of said inlet and outlet valve devices one of said inner members being adjustable relative to the other.

14. In apparatus of the character described, the combination of a series of liquid holders, inlet valve devices comprising an inner member and an outer member, one of which is rotatable relative to the other, the outer member being formed with a series of openings and the inner member being formed with a port or duct to control the flow of liquid through the openings in the outer member, outlet valve devices comprising an inner member and an outer member, one of which is rotatable relative to the other, the outer member being formed with a series of openings and the inner member being formed with a port or duct to control the discharge of liquid through the openings in the outer member, a liquid supply connection between each opening in the outer member of the inlet valve devices and one of said holders, a liquid discharge connection between each of the openings in the outer member of said outlet valve devices and one of said holders, and means for operating the rotatable members of said inlet and outlet valve devices, the control ports of the said inner members of said inlet and outlet valve devices being disposed in different positions angularly, relatively to each other, to register simultaneously with one opening for the liquid supply connection of one holder and one opening for the liquid discharge connection of another holder, whereby one holder may be filled while the other is emptied.

15. In apparatus of the class described, the combination of a series of liquid holders, a series of supply pipes, each connected to one of said holders, the inner ends of said pipes being arranged in the same plane and about and an equal distance from an axis, a valve rotatable about the axis common to the inner ends of said supply pipes and arranged to successively register therewith, a series of discharge pipes, each connected to one of said holders, the inner ends of said discharge pipes being arranged in the same plane and about and an equal distance from an axis, a valve rotatable about the axis common to the inner ends of said discharge pipes and arranged to register successively therewith.

16. In apparatus of the class described, the combination of a series of liquid holders, a series of supply pipes, each connected to one of said holders, the inner ends of said

pipes being arranged in the same plane and about and an equal distance from an axis, a valve rotatable about the axis common to the inner ends of said supply pipes and arranged to successively register therewith, a series of discharge pipes, each connected to one of said holders, the inner ends of said discharge pipes being arranged in the same plane and about and an equal distance from an axis, a valve rotatable about the axis common to the inner ends of said discharge pipes and arranged to register successively therewith, and means for operating said valves.

17. In apparatus of the class described, the combination of a series of liquid holders, a series of supply pipes, each connected to one of said holders, the inner ends of said pipes being arranged in the same plane and about and an equal distance from an axis, a valve rotatable about the axis common to the inner ends of said supply pipes and arranged to successively register therewith, a series of discharge pipes, each connected to one of said holders, the inner ends of said discharge pipes being arranged in the same plane and about and an equal distance from an axis, a valve rotatable about the axis common to the inner ends of said discharge pipes and arranged to register successively therewith, means, including a shaft, for connecting said valves together, and means for operating said shaft.

18. In an apparatus of the class described, combination with a plurality of vats grouped about a common center, of a centrally located shaft, a receptacle for the incoming milk carried by the top of the shaft, and having an eccentrically located discharge aperture, a receiving member for each of the vats with which the discharge aperture is adapted to register seriatim, and means for rotating the shaft.

19. In an apparatus of the class described, the combination with a plurality of vats grouped about a common center, of a centrally located shaft, a receptacle for the incoming milk carried by the top of the shaft and having an eccentrically located discharge aperture, a receiving member for each of the vats with which the discharge aperture is adapted to register seriatim, and means for rotating the shaft, each of said members having a pipe extending therefrom to the bottom of its associated vat.

In testimony whereof I affix my signature, in the presence of two witnesses.
